10 Claims. (Cl. 73—229)

This application is a continuation-in-part of my application Serial No. 789,370, filed January 27, 1959, now abandoned.

This invention relates to apparatus responsive to the velocity and rate of flow of a fluid medium flowing across a surface, and is particularly concerned with a flowmeter for measuring the rate, and volume of the flow of a fluid medium.

Existing instruments for measuring the rate of flow of a fluid medium, are almost exclusively flowmeters concerned with measuring the rate of flow of a fluid medium through a conduit, and these may be divided into two broad classes.

The first of these is that type in which the fluid medium is forced to undergo a constriction in its flow path, thereby causing an increase in the flow velocity, and hence a corresponding reduction in the static pressure. The pressure differential existing between the free flow, and the constricted flow areas, is then a measure of the flow velocity and by measuring this pressure differential by suitable means, such as, for example, a manometer, the flow velocity can be measured. The most common ways of creating the constriction in the flow path are by a throat in the conduit, i.e. a Venturi meter, or alternatively by introducing an orifice plate into the flow stream. This type of equipment is sensitive to variations in atmospheric pressure, temperature, etc., and also in general, the pressure differential that the measuring equipment is capable of accommodating is quite limited, so that the equipment may be only used with a prescribed type of fluid medium flowing under certain specified conditions. This type of flowmeter is frequently found in large installations where information on flow velocity is all that is required, since it is difficult to translate the flow velocity, as given by the pressure differential, into a conveniently calibrated rate of flowmeter, and from this into a volume of flow. This is complicated by the use of conversion tables or by the use of auxiliary evaluating equipment.

In the second class of flowmeter most commonly employed today, a rotating vane or propeller, which may take the form of a helically formed rotor, is placed in the center of the flow path of the fluid medium with its axis of rotation parallel to the direction of flow. As the fluid medium flows through the rotor it causes it to rotate, and the speed of rotation varies in sympathy with the variation in the flow velocity, so that by suitable connection to this rotating member an indication may be obtained of the rate of flow. This system has several obvious drawbacks, not the least of which is the impediment introduced into the free flow path of the fluid medium by the presence of the rotating vanes and associated supporting members which must, of course, also project into the flow path. Impeding the flow in this manner causes the flow to become disturbed, particularly when the flow velocity exceeds a certain value, and also there is an appreciable energy loss in the kinetic energy of the fluid medium. The mechanical inertia of the moving

2

parts in this system is a serious drawback since it means that the response of the system to changes in flow velocity is sluggish, and also that at low flow velocity the accuracy of the system is very dubious since an appreciable flow velocity is required before the vanes even start to rotate. Another drawback is that at high velocities the accuracy is affected by the fact that the vanes must, by their very nature, be supported on a downstream thrust bearing and as the flow velocity varies the pressure exerted on this thrust bearing will vary in sympathy and so there is introduced a variable factor which affects the accuracy of the system. To obtain the best results high precision work, profile milling, and balancing of the vanes is required and is very costly.

15 There is disclosed in the present invention apparatus for measuring the flow velocity of a fluid medium through a casing which has the virtue that little or no impediment is offered to the free flow of the medium and which has the additional benefits of simplicity of design and lowered 20 manufacturing costs and coupled with the fact that the information regarding the flow velocity, and also the volume of flow, may be extracted in a relatively simple manner with proven equipment which uses the minimum of moving parts, none of which are disposed in the main flow 25 stream, so that the mechanical inertia of the mechanical system is as low as possible and its accuracy is relatively unaffected by varying flow velocity.

A characteristic of the present invention is that, in all 30 its different embodiments, it utilizes the property common to all fluid media when flowing over a surface, that there is created at the point where the fluid medium comes in contact with the surface a boundary layer, caused by the fact that the fluid medium in actual physical contact with the surface "sticks" to this surface and so its velocity is 35 zero, inwardly from the surface the velocity of the fluid increases until it becomes substantially constant. The layer or thickness or depth over which the fluid velocity is rapidly increasing away from the surface is known as 40 the boundary layer.

The basis of the present invention is the utilization of 45 the knowledge that when a fluid medium is flowing through a casing, a rotating member comprising a single plate which has an aerodynamically designed profile can be so positioned with its axis of rotation transverse to the direction of flow of the fluid medium through the casing that it is possible to cause three different forces to act 50 upon the rotating member as it rotates, each force producing a turning moment tending to rotate the rotating member in the same direction, and sufficient in the aggregate to sustain continuous rotation of the member at a speed proportional to the flow velocity of the fluid medium through the casing. These three forces which may be 55 best considered respectively as aerodynamic lift, dynamic, and static pressure forces, must of course represent an energy loss from the flowing fluid medium but the loss is very much smaller than that encountered in any other known form of flowmeter and an extremely small impediment is offered to the passage of the fluid medium by the 60 flowmeter disclosed in this invention. Thus the manufacture of this new flowmeter is simplified at less cost.

When formed according to this invention a flowmeter 65 for determining the rate of flow of a fluid medium comprises a casing, means defining a flow path for said fluid medium through said casing, means for increasing the cross-sectional area of said flow path in a downstream direction over at least a portion of said flow path, means

defining at least one cavity in said portion of said flow path, a single rotating blade member having an aerodynamically designed profile mounted in said cavity for rotation about an axis transverse to the direction of flow of said fluid medium through said casing at said cavity, and also parallel to the mean plane of the flow surface of said casing adjoining said cavity, and means associated with said rotating member having an output proportional to the speed of rotation of said member, said rotating member in its rotation having at least one position whereat one edge of said member projects into the main flow stream of said fluid medium through said casing and a second position whereat said single rotating blade member is contained substantially entirely within said cavity, whereby to cause said rotating member in rotating to experience successively aerodynamic lift, dynamic, and static pressure forces each tending to rotate said member and sufficient in the aggregate to sustain continuous rotation of said member.

The information concerning the angular rotational velocity of the rotating member may be extracted by conventional mechanical or electro-mechanical means or alternatively a novel electrical sensing unit disclosed in this invention may be used which permits the rotational information to be extracted in the form of electrical signals, which may then be processed in a variety of ways in order to present the flow velocity or the volume of flow information in whatever form is most appropriate for the particular use to which the invention is to be put.

The novel electrically-energised sensing unit of the present invention includes a reactance circuit element, such as a coil or a condenser, which is part of an oscillator positioned so that its reactive impedance varies in sympathy with the rotation of the rotatable member in the cavity whereby the generated electrical signals appear as modulation of a high frequency carrier in the output.

In connection with the use of the word "constriction" in the present specification, this word is employed in the sense in which it means contraction followed by expansion in general back to the original pre-contracted level, and will be used in this specific manner throughout this specification, including the claims.

A greater understanding of the basic inventive concept of the present invention, and of the manner in which it is employed in practice, will be gained from the study of the following description of certain flow theory associated with the invention, and of the various embodiments disclosed, when taken in conjunction with the accompanying drawings in which

FIGS. 1, 2 and 3 show in cross-section the principal components of a preferred embodiment of a flowmeter formed according to the present invention, the rotating member in each of the figures being shown in a different position where a different type of rotational force is being experienced by the member.

FIG. 1 shows the position of the rotating member when it is experiencing a static pressure rotational moment.

FIG. 2 shows it when it is experiencing an aerodynamic lift rotational moment; FIG. 2a showing the aerodynamic lift and drag forces and their resulting rotational moment.

FIG. 3 shows the member in the position where it is experiencing a dynamic pressure rotational moment.

FIG. 4 shows a side elevation in cross-section of a flowmeter formed as a preferred embodiment of the present invention;

FIG. 5 shows an end elevation of the flowmeter of FIGURE 4 along the lines 5-5 of FIGURE 4;

FIG. 6 shows two different types of rotatable members which are preferably used, FIGURE 6a showing a flat member, and 6b showing a twisted member;

FIGURE 7 illustrates in diagrammatic form how the sensing element is used to extract the rotational information of the rotating member of FIGURES 4 and 5;

FIG. 8 is the block diagram of an electronic circuit which may be suitably associated with the sensing element of FIGURE 7 to give the desired rate, and volume, of flow information;

5 FIGURES 9a and 9b show the modulation envelopes at different rotational speeds for the modulated carrier of FIGURE 8, and

10 FIGURES 10a and 10b show the resultant output wave form from FIG. 9. FIGURE 10a showing the output wave form immediately after detection, and FIGURE 10b showing the output wave form after detection and clipping;

15 FIGURE 11 shows an alternative configuration for the sensing element used in conjunction with the flowmeter of FIGURES 4 and 5. FIGURE 11a showing an end elevation of this sensing element, FIGURE 11b showing a side elevation of this sensing element and FIGURE 11c showing how the end of the rotating member may be modified to give a more desirable velocity rotation speed calibration;

20 FIGURE 12 shows an alternative construction for the flowmeter shown in FIGURES 4 and 5. FIGURE 12a being a cross-section in elevation, and FIGURE 12b being a perspective view with a side plate removed;

25 FIGURE 13 shows yet another form of construction of a flowmeter. FIGURE 13a showing a detail of the actual measuring sub-assembly. FIGURE 13b showing an end elevation in cross-section of the complete assembly, and FIGURE 13c showing a plan view of the assembled flowmeter;

30 FIGURE 14 shows a comparison of the velocity diagram and associated physical layout of a flowmeter of the type shown in FIGURES 4 and 5, with those for a flowmeter having only one rotating member disposed on either side of the flow path, and FIGURE 14b showing the asymmetrical arrangement and velocity diagram when only one rotating member is disposed adjacent the flow path;

35 FIGURE 15 shows the construction of a modified form of rotational member which is more suitable for particular types of flow measurement.

40 FIGURE 16 and FIGURE 17 shows a removable sub-assembly which houses the rotating member and its bearings and which may be removed without interrupting the fluid flow for maintenance purposes.

45 FIGURE 16 showing the sub-assembly in cross-section transverse to the direction of flow,

50 FIGURE 17 showing the sub-assembly in cross-section parallel to the direction of flow,

55 FIGURES 1, 2, 2a and 3 are included to give an explanation of the manner in which the system works and show the principal components of the system with the rotating member in different positions of its rotational arc.

60 It will be seen that the system comprises a casing C, through which flows a fluid medium in the direction of the arrow, the flow path of the medium normally being of circular bore, but here, for convenience, it may be considered as being of rectangular bore. A constriction, by which is meant a uniform contraction in the flow path area followed by a uniform expansion in the flow path area, is brought about by means of the projection P which rises from one side of the casing C, its surface following the contours normally associated with the Venturi type of meter, this of course being the form which gives smoothest contraction and expansion.

65 Downstream of the point of maximum constriction a cavity R is formed in the projection P. The inner surface of the cavity is, for reasons given below, preferentially made cylindrical in form, except where the downstream edge merges with the flow surface, the axis of the cylinder being transverse to the direction of flow of the fluid medium past the cavity.

Positioned in the cavity R and having its axis of rotation coincident with that of the cylinder, when the cavity is so formed, is a single rotating blade member B. As shown here, the member has a generally aerodynamically designed profile. Opposed edges of the member B are close to, but maintain constant separation from, the inner surface of the cavity R as member B rotates.

Referring to FIG. 1 it will be seen that the rotating member B and cavity R are so dimensioned, and positioned, that the rotating member can lie in a position generally parallel to the flow of the fluid medium past the cavity R with both tips adjacent the inner flow surface of the cavity R that is with the single rotating blade member contained entirely or substantially entirely within the cavity R. This being the case, the fluid medium on the underside of the member B is essentially a closed body and presents uniform pressure to the underside of the aerodynamically designed profile of member B. On the upper surface the increasing cross-sectional area of the flow path causes a downstream increase in the static pressure present upon the upper surface of the aerodynamically designed profile of member B. This means that the advance or upstream edge A is subject to less static pressure than is the trailing or downstream edge T, and this disparity of pressure produces a rotational moment tending to rotate the member B in the direction shown.

In FIGURE 2 the static pressure force has rotated the member to the point where the advance edge A is clear of the projection P and is starting to penetrate the flow stream. Here conditions are as shown in FIGURE 2a. The fluid medium flowing in the direction of the arrow meets the streamlined aerodynamically formed profile, and creates on it, in the manner of other aerofoils, lift and drag forces which act through a point substantially offset from the axis of rotation E towards the leading edge A of the member B. Both the lift and drag forces, but principally the lift force, have components which lie in a direction perpendicular to the "chord" axis of the profile of member B, this being represented in FIGURE 2a by the vector F. This force is offset by a distance r_F from the axis of rotation E so that a turning moment of $F \cdot r_F$ acts to rotate the member B.

In FIGURE 3 the member B has rotated to the point where the advance or upstream edge A has penetrated appreciably into the flow stream and is experiencing a dynamic pressure due to the flowing medium (as exemplified by streamline S) which produces a tangential torque continuing the rotation of the member back to the position shown in FIGURE 1 when advance A and trailing T, edges will have interchanged themselves in the 180° cycle. It will be obvious from the symmetry of the rotating member that the cycle will then repeat itself.

It will be noted that in FIGURES 2 and 3 the proximity of the trailing edge T to the inner surface of the cavity R isolates the advance edge from any interfering flow patterns which would occur if such proximity with the inner flow surface was not maintained. Thus the configuration shown gives maximum benefits but it should be borne in mind that the cavity may have other less efficient forms without rendering the system unusable, so that the cylindrical inner flow surface for the cavity R should be regarded as the preferred, but not the essential, form of this surface.

Similarly though symmetry about its axis of rotation may be regarded as essential, there may in fact be profiles for rotating member B which are not so symmetrical. More will be said later of possible profile forms in connection with FIGURE 6.

One preferred form of flowmeter is shown in FIGURES 4 and 5. The flowmeter generally indicated by the reference numeral 1, comprises an outer casing 17 having a cylindrical bore through it, effectively forming a length of conduit, and which is capable of connection at either end to any pipe through which the fluid medium may be flowing. The diameter of this bore is D. From

the intake region 2 the cross-sectional area of the flow path contracts to a central region 3 where the flow path is of reduced vertical dimension d. Downstream beyond this constricted area 3 the flow path again widens until it returns to the original conduit dimension D in the outlet region 4. The contraction in the flow path is introduced smoothly and continuously by the inlet portion 5 and the outlet or diffuser portion 6 expands the flow path gradually and smoothly on the downstream side, the flow surfaces of these portions being of high finish to minimize disturbance. Sections 5 and 6 are integrated with the casing 17 either by being fabricated separately and then attached by suitable means such as brazing or welding, or alternatively may be cast in one unit with the casing. As will be best seen from FIGURE 5, these two portions, in this particular embodiment, are not annular as is the case with a venturi meter but have substantially flat inner surfaces forming chords of the circle defined by the bore of the casing 17 so that the constricted area 3 is very nearly rectangular in cross-section with straight upper and lower edges and curved side edges.

The amount of constriction of the cross-sectional area of the flow path obviously governs the extent to which the velocity of the fluid medium is increased and in a typical example the ratio of the cross-sectional area of the free flow path i.e. in the open conduit of diameter D, to the constricted area i.e. at the point where the vertical dimension of the flow path has been reduced to small d, was approximately 3:2, which caused a velocity increase in the ratio of 1.6:1, as given by the equation derived from the fact that the quantity of flow is constant, namely.

$$A \cdot v_{av} = C_c \cdot a \cdot v_c$$

where A is the area of the bore of diameter D, v_{av} is the mean velocity, C_c is the co-efficient of contraction, and is given by the ratio of the calculated cross-sectional area of the flow path at the vena contracta, to the cross-sectional area a of the flow path at the point of maximum constriction, a is the cross-sectional area at this point of maximum constriction, and v_c is the mean velocity of the fluid medium at a point of maximum constriction. The angles of the flat inner flow surfaces of the inlet and outlet positions 5 and 6 subtend with the bore axis are critical since the constriction in the flow path of the fluid medium should be accomplished smoothly and continuously without either excessive contraction or excessive expansion. The angle of the inlet portion 5 preferably lies in the range of 10 to 20 degrees and the angle of the outlet portion 6 in the range of from 5 to 15 degrees. In a typical flowmeter the two angles were 14 degrees and 10 degrees respectively.

The inlet and outlet portions 5 and 6 are in line with one another, and the cross-sectional area of the flow path at the downstream edge of the inlet portion is made less than that at the upstream edge of the outlet portion, so that between these two points the cross-sectional area of the flow path increases in a downstream direction.

These two portions are spaced apart in a downstream direction and the interruption in their surfaces defines the limits of a central portion of the assembly, the outer edges of this central portion thus being contiguous to and merging smoothly with those of the inlet and outlet portions. At the point of maximum constriction there are located therefore upper and lower central portions, in which are diametrically opposed cavities 7, which are designed for optimum performance in the manner described above, each cavity extending transversely to the direction of flow for substantially the full width of the conduit. In each of these cavities is located an aerodynamically designed member 8, which may have various forms as described below.

The positioning of the rotating member in the cavity has been described above and is such that the longitudinal axis, about which the rotating member 8 rotates, and which will normally be the longitudinal axis of symmetry, is dis-

posed transversely to the direction of flow of the fluid medium, and at the same time parallel to the plane of the boundary layer of the main flow moving across the cavity opening, the exact position of this plane is difficult to define since it may be curved in certain applications where the downstream edge of the inlet portion is not flat across its entire width, and it is perhaps better to define the position of the axis as being parallel to the mean plane of the flow surface adjoining the cavity.

At either end of each rotating member 8 is a journal shaft 21 as is best seen in FIGURE 5. These shafts are journalled into bearings 22 and 23 respectively at either end of the rotating member which support this member 8 for rotation about the longitudinal axis. Bearing 22 mounts directly in the casing sealed off by seal 24 but bearing 23 is mounted in a bearing block which in turn screws into the casing. The member is first inserted through the bore which houses the block for bearing 23 until it engages the bearing surface of bearing 21, when the block for bearing 23 is inserted and screwed into place. The bearing assembly is sealed off on either side by two side plates 25 which are held in position by screws 26.

For the average type of duty the rotating member 8 may most conveniently, and preferably, have the form shown in FIGURE 6a. However, other applications may produce variations in the profile of this rotating member, and also may require variations in the profile placement along the axis of rotation. For example, it may be desirable in certain applications to use the modified form of construction shown in FIGURE 6b, where the chord axis of the rotating member shown in FIGURE 6a has been rotated slowly but continuously and unidirectionally throughout its length, producing a helical twist in the member. The advantage of this construction is that it tends to level out the rotational forces since one portion of the member will be undergoing dynamic or static pressure forces while another is experiencing aerodynamic lift and so on depending on the degree of twist. Thus a more uniform rotational moment can be produced but at the expense of some interaction between the forces along the length of the member, giving slightly increased energy losses.

Other profiles may be dictated by the type of fluid medium being measured, and also its velocity. Thus, for example, in very high speed measurements it may be preferable to use a rotating member whose profile is essentially a low diamond shape, and again an S-shaped profile may be preferable when it is desired to obtain most effect from the dynamic pressure forces.

The profile of the rotating member must therefore be determined for the specific application to which the flowmeter is to be put, but of course any given flowmeter will cover a broad range of fluid mediums and flow velocities. An example of this particularly is described below in connection with FIGURE 15 which shows a rotating member structure designed for use in flowmeters which must be sensitive to low flow velocities.

The structure as described thus far will on the passage of a fluid medium through the bore of the flowmeter, cause the rotating member 8 to rotate at a speed proportional to the main flow velocity of the fluid medium, but to be useful it is necessary that the flowmeter also include some means which, in association with the rotating member will give an output proportional to the speed of rotation of the member. The mechanism used, whatever its nature, will obviously have to be mounted in such a manner that it can respond to the rotation of the rotatable member, and may be suitably housed in a housing integrated with the main casing of the flowmeter in the manner depicted in FIGURES 4 and 5 for unit 13.

The simplest and most direct means known of extracting information as to the rotation speed of a shaft are, of course, mechanical, or alternatively electro-mechanical. Examples will be a tachometer or speedometer directly driven by the shaft used to indicate the rate of flow, with

an auxiliary gear drive for giving the volume of flow, in much the fashion that the speedometer of a car is arranged, or an electric motor could be used with its rotor driven by the member shaft. A variety of ways readily suggest themselves but all have the disadvantage that they require mechanical connection to the rotating member increasing its inertia, and hence the speed of response of the system. Where this is of little practical consequence these means can be usefully employed, but for those situations where this factor becomes critical a novel sensing unit has been devised as is shown in the cross-sectional view of the upper unit 13 of FIGURE 4.

This unit is inserted in an annular cylindrical housing 14 which may suitably be cast with the casing 17. Inside 15 this housing there is positioned an inductance coil 10 with its longitudinal axis generally normal to the axis of the bore and also at right angles to the longitudinal axis of the rotating member 8. Axially inside this coil 10 there is introduced an iron core 11 which acts as a tuning slug 20 for the coil. The coil 10 is mounted on a bed of non-magnetic material 12 which is let into the wall of the casing 17, non-magnetic material is used so that any electro-magnetic field created around the coil is not affected by the presence of this mounting 12 which thus serves as a membrane. The membrane 12 is in turn held in position by a sealing gasket plate 18 which also serves to keep the coil 10 in place. Surrounding the coil and fixing plate 18, is a mounting of similar non-magnetic material 19, which in turn is fixed firmly in position by the retainer 9, 30 on top of which is placed plate 20 which includes an electrical connector 16 from which contact is made to the terminals of the coil 10. The whole assembly is kept in place by the cap 15 which is securely attached to the housing 14.

35 The manner in which the coil and the member 8 cooperate is best understood by having reference to FIGURE 7 where it will be seen that the lines of force F set up around the coil 10 are periodically broken by the member 8 as it rotates, for in one position shown, the member 8 lies substantially normal to these lines of force, and in the other position it is substantially parallel to them. Thus as the member rotates it cuts the lines of force F every half cycle of revolution thereby effectively varying the reactive impedance of the coil 10 every half revolution of the rotating member 8.

30 The lines of force F are set up around the coil by electrical energy which is fed to the coil 10 from a suitable outside source. This source is here a high frequency oscillator and the sensing coil 10 forms the inductive part 50 of the high frequency oscillator tuning circuit.

The manner in which this varying impedance is utilized may differ with the application to which the flowmeter is to be put but a typical circuit is shown in block diagram form in FIGURE 8. The coil 10 is included as part of 55 the winding of an oscillator coil for the oscillator 111 which will, in the absence of any rotation of the rotating member 8, therefore have a fixed frequency output. A second, constant-frequency, oscillator 110 has a slightly different frequency from that of oscillator 111, so that, 60 much in the manner of the oscillator coils of a super-heterodyne receiver, in the absence of any rotation of the rotating member 8, the two frequencies of oscillator 111 and oscillator 110 are mixed together to provide a constant frequency output. This constant frequency output is fed through the intermediate, or I.F., amplifier 112 to the detector 113. From here the detected output is fed to the pulse separator 114 which performs two functions. Firstly, the peak D.C. level of any input of the detector is determined and combined with a fixed D.C. potential from 65 the densitometer 116, and is then fed to the rate of flowmeter 115, and secondly any modulation peaks present in the output from the detector 113 are clipped and shaped and fed through the pulse counter 117 to the quantity or mass flow, meter 118.

70 The manner in which the circuit functions is as fol-

lows: when the member 8 starts to rotate it alters the reactive impedance of the coil 10 which is turned for optimum performance by means of the tuning slug 11. As this impedance varies with every half revolution it effectively modulates the beat frequency emerging from the frequency converter stage of oscillator 111. Varying the speed of rotating member 8, in addition to varying the frequency of the modulation envelope, also affects the percentage of modulation of the basic carrier frequency, since the more rapidly the rotating member 8 cuts the lines of force F of coil 10 the greater the variation in the impedance of the coil, so that an increase in the rotation speed of the rotating member is accompanied by an increase in the modulation frequency, and also in the percentage modulation of the carrier.

This is shown in FIGURE 9, where FIGURE 9a shows the resultant intermediate frequency modulated wave form for a low revolution number and FIGURE 9b shows that for a high revolution number.

After detection these two wave forms emerge as shown in FIGURE 10a. Both oscillate about the same mean D.C. level, E_m , though at different frequencies and to different peak levels. To this mean D.C. level E_m , there has been added a constant D.C. potential E_d whose value is established by the densitometer 116, and which represents a variable D.C. component provided to compensate for differing densities of the fluid flowing through the flowmeter, so that the output of the electronic system will not be subject to error through variations in the density of the fluid medium.

In the separator 114 the positive going output wave forms shown in FIGURE 10a are separated into two parts. The first portion is passed through a smoothing filter which gives an output D.C. level proportional to the peak value of the rectified wave form, so that even through the two wave forms shown are oscillating about the same average D.C. level, E_m , their peak levels, E_1 and E_2 respectively, are different due to the difference in the percentage modulation mentioned above. Accordingly the higher the revolution number the greater the D.C. potential emerging from the separator unit 114. The D.C. potential is fed to the rate of flowmeter 115, which may suitably be a D.C. voltmeter appropriately calibrated in rate of flow units (gallons per hour, etc.) and the higher the revolution rate of the rotating member 8 the greater the D.C. level which will emerge from the separator unit 114 and accordingly the higher the rate of flow shown on meter 115.

Also in the pulse separator unit the other portion of each of the wave forms is D.C. restored or clipped, for example by passing them through a capacitor and then a rectifier, so that only the positive going half cycle of each wave form emerges in the manner shown in FIGURE 10b. Here the two wave forms have first been filtered so that they oscillate about the zero voltage level, and have had their negative-going half-cycles removed so that they now emerge as a series of positive going pulses, with the number of pulses in any given period being dependent upon the frequencies f_1 or f_2 , i.e. the revolution rate, so that the higher the speed of revolution of the rotating member 8, the greater the number of pulses emerging from the separator unit 114 and being fed to the pulse counter or integrator unit 117. In this unit the number of pulses in any given period is added to give an output from the integrator unit 117 proportional to the number of pulses received in any given period of time. Since the number of pulses depends upon the rate of flow the total number of pulses in any given period of time is proportional to the total volume flowing in that time, and so the indicator 118 will indicate the actual volume and mass of the fluid medium which has flowed through the conduit in any given period and again this may suitably be a D.C. voltmeter calibrated in gallons, etc. Alternatively each pulse can be used to actuate a step solenoid, which in turn advances a Veeder-Root type counter.

From the foregoing it will be appreciated that this electrically energised sensing unit obtains its output proportional to the speed of rotation of the rotating member, by having this member as it rotates vary the reactive impedance of a reactance circuit in sympathy with the rotation. To do this of course it is necessary that at least part of the rotating member either be made of, or incorporate in its structure, material, such as a ferrous alloy, whose presence evokes this response.

10 The same circuit configuration as described above, may be used in conjunction with other means of developing the variable reactive impedance due to the rotation of the rotating member, one of which is shown in FIGURE 11. Here a condenser unit has been positioned above the 15 journal shaft 21 which fits into the bearing 22. Above this shaft is located a housing 27 fitted as before with an electrical connector 16; to the electrical connector are joined two leads which pass through a seal 29 into the area above the shaft 21. One of these leads goes to a capacitor plate 27 which may be a simple rectangle in form and the other to a brush contact 28 which makes contact with the shaft 21 and thence with the rotating member 8. There is thus effectively formed a condenser of known 20 capacitance between the plate 29 and the rotating member 8 by means of the brush contact 28. It will be obvious that as the rotating member 8 rotates the capacitance present between the two leads connected to plate 27 and brush contact 28 will vary in sympathy with the rotation of the rotating member and will do so twice 25 every revolution of the member. This varying capacitance creates a varying reactive impedance in the manner described above for the coil 10 and its output may be processed in the same manner.

30 In order to give a more discrete and appreciable capacitance variation the end of the rotating member 8 may be modified in the manner shown in FIGURE 11c by attaching a capacitive plate 30 to the end of the member 8, this plate being so shaped that the variation in capacitance present between the two terminal contacts gives 35 an output more suitable for processing in the electronic circuit.

35 In order to obtain the benefits conferred by symmetry of flow, the flowmeter shown in FIGURES 4 and 5 had two cavities, two rotating members and two sensing units 40 diametrically opposed on either side of the flow path. It should be obvious that only one system is necessary to give the rate of flow information and the manner in which the flowmeter behaviour is modified in this case is described later in connection with FIGURE 14, the second rotating member of the flowmeter of FIGURES 4 and 5 is far from being superfluous however, since it provides backup protection if one unit should fail and also it is a relatively simple matter to add an averaging circuit, which has as its output a reading equal to the mean 45 value of the flow velocity as indicated by each rotating member increasing the reliability of the system. Further by installing rotating members each with a different profile the measurement range and accuracy can be increased.

60 The manner of constructing the flowmeter can also be varied in various ways to improve the product and to cut down production, assembly, and maintenance costs one of which is shown in FIGURE 12. Here the flowmeter 1 has been made in three parts, an inlet section 65 which contains the inwardly curved inlet portions 5, a central section containing the rotating member 8 chambers and the sensing units 13, and an outlet section containing the outwardly curved outlet or diffuser portion 6. This facilitates manufacture and assembly of the unit and also 70 means that, should a part need replacing in the field, it is not necessary to replace the entire unit but merely the section which is defective, which will usually be the central section containing rotating member 8 and the sensing units 13. The manner in which the units are assembled is shown in FIGURE 12b, which depicts the 75

side plate 25 and its retaining screws 26 removed in an exploded view.

Yet another type of construction is shown in FIGURE 13, here the flared inlet and outlet portions 5 and 6, together with the rotating member 8 in their associated cavities 7, are formed as one unit mounted on a sealing pad 32 which in turn is mounted on a base plate 33. The sensing units are housed in a compartment 31 in the inlet portion 5, as shown in FIGURE 13a. In use the complete assembly is inserted into the casing 17, in the manner shown in FIGURES 13b and 13c, and the flow stream at this point is therefore divided into two portions each of which flows past a different cavity.

It should be noted that the velocity diagram with this configuration will vary somewhat from that for the flowmeter of FIGURES 4 and 5 where the two cavities were symmetrically disposed on either side of the conduit. The velocity diagram for that constriction is, as shown in FIGURE 14a, i.e. a virtually flat top curved with some flow reversal at the two cavities. With the configuration shown in FIGURE 13, the velocity diagram will be modified in the manner shown in FIGURE 14b where only one rotational system is depicted mounted opposite a flat walled conduit 17. Here the velocity inwardly of the conduit flow surface increases up to the cavity in a generally uniform manner and then abruptly reverses as the velocity diagram shows. It will be obvious that the velocity reading indicated in these two cases will be different even though the constriction in the flow path be the same. This however, can be calculated and compensated for in the electronic circuitry described above, this being one of the inherent advantages of this type of unit in that, due to the absence of mechanical connection and the relative ease with which variations can be made, or corrections applied, to the output, various types of configurations for the different types of flowmeter can be used with a minimum of adjustment.

In the flowmeters described so far the rotating member has been in the form of a single unit. From the description accompanying FIG. 1 it will be recalled that in certain positions the rotating member may be subject to only static pressure forces, and this force considered alone, particularly at low flow velocities, does not produce as substantial a rotational movement as do the aerodynamic and dynamic pressure forces. Thus if by chance the rotating member stops in the position shown in FIG. 1, and the fluid medium is then passed through the flowmeter at low velocity, or alternatively if the flowmeter is stopped and started frequently, as for example in a domestic gas or water meter, the slow starting response with the rotating member in this position is a disadvantage. It is true that the response of the member to a given pressure differential can be increased by the use of high precision bearings, light weight materials, etc., but this expense is not necessary.

The helically twisted rotating member shown in FIG. 6b offers a solution to this problem, but a large amount of twist is normally necessary, between 45° and 90°, and this considerably lowers the lift forces produced on the rotating member and also the effect of the dynamic forces, another by-product being the generation of a side force thrusting on one of the support bearings for the rotating member; the general result being a lowered overall efficiency.

A form of rotating member construction which gives fast response but without the efficiency losses of the twisted member is shown in FIG. 15. It will be seen that the rotating member is now formed in two identical sections 81 and 82 lying along a common axis but with their chord axes at right angles to one another. Shaft 21 projecting from each end is used for mounting the member. Now if one section should stop in the position where it will only experience static pressure when flow starts again, the other member section will be positioned so as to experience maximum dynamic pressure producing immediate response

on the rotational member. There is some reduction of lift force in this modified rotating member construction, and also there would be an aerodynamic interaction between the two sections, but this is prevented by the presence of the disc 40 interposed between the two sections 81 and 82 which prevents any such interaction.

As a practical form of construction the shaft 21 may be made of steel, the two sections 81, 82, of plastic material, and the disc 40 of alternate quadrants 41, 42, 43 and 44 (not visible) of similar metals welded together to produce different signal levels in the electronic sensing unit which extracts the information as to the rotating member velocity.

In use it is possible that the bearings for the rotating member will need replacement, or else this member itself will need attention. In this case it would be useful to be able to remove the member and bearing assembly without disturbing the flow of the fluid medium through the flowmeter, as the other rotating assembly could continue to supply flow velocity information. Such a subassembly is shown in FIGS. 16 and 17.

The inner flow surface of the cavity 7 is made in the form of a cylindrical steel or brass liner 51 provided with an appropriately contoured slot 55 communicating the cavity with the main flow stream, and also a non-metallic insert 56 which permits the member 8 in rotating to affect the sensing coil 10 in the response unit 14. The rotating member 8 is positioned in this cylinder and supported on bearings 22 and 23 so that the liner 51 and its associated rotating member and bearings provide a neat sub-assembly.

This cylinder or liner 51 is positioned in a support block 50 attached to the conduit 17 and is a tight fit in this block, and also, of course, fits tightly against the inlet and outlet portions 5 and 6.

In normal use the sub-assembly is positioned in the block. The slot 55 exposes the rotating member to the flow stream, and the end caps 52 (see hereon one end only in FIG. 16) seal the unit.

However, in case the assembly has to be removed, the steel cylinder or liner 51 is rotated by any suitable means, for example notches cut in one end, until the solid portion of the liner covers the entrance to the cavity 7, thus sealing the sub-assembly from the fluid medium.

The end caps may then be removed and the sub-assembly extracted. But of course the gap made by the removal of the sub-assembly must be closed, and this is done by means of a tool rod 53 in the form of a brass or similar cylinder of identical diameter to the liner 51. This tool rod 53 may conveniently have a threaded projection 54 at one end which engages a threaded bore on the inner surface of liner 51 (and thus when tightened will provide a means of rotating the liner 51), so that no interruption in the seal against the fluid medium is made as the rod is tapped to push out the sub-assembly. Once the sub-assembly emerges on the far side unscrewed from the rod and sent away for attention, the rod remaining in place until the sub-assembly is replaced.

I claim:

1. A flowmeter for determining the rate of flow of a fluid medium, comprising a casing, means defining a flow path for said fluid medium through said casing, means for constricting the cross-sectional area of said flow path in a downstream direction to a point of maximum constriction, means for increasing the cross-sectional area of said flow path in a downstream direction from said point of maximum constriction, means defining a cavity in the flow surface of said cross-sectional area increasing means adjacent to but downstream from said point of maximum constriction of said flow path, a single rotating blade member having a profile of aerodynamic design mounted in said cavity for rotation about an axis transverse to the direction of flow of said fluid medium through said casing at said cavity, and also parallel to the mean plane of the flow surface of said casing adjoining said

cavity, and means associated with said member having an output proportional to the speed of rotation of said member, said member in its rotation having one position whereat one edge of said member projects into the main flow stream of said fluid medium through said casing and another position whereat said rotating member is contained substantially entirely within said cavity, whereby to cause said member when said fluid medium flows through said flow path to experience successively aerodynamic lift, dynamic, and static pressure forces each tending to rotate said member and sufficient in the aggregate to sustain continuous rotation of said member.

2. A flowmeter for determining the rate of flow of a fluid medium comprising a casing essentially defining a length of conduit of varying cross-section, said casing comprising an inlet portion wherein the flow surface of said casing converges smoothly and continuously in a downstream direction whereby to decrease the cross-sectional area of the flow path of said fluid medium, an outlet portion downstream of said inlet portion wherein the flow surface of said casing diverges smoothly and contiguously in a downstream direction whereby to increase the cross-sectional area of the flow path of said fluid medium, a central portion connecting said inlet and outlet portions and having the outer edges of its flow surface contiguous with those of said connected portions, means defining a cavity in the flow surface of said central portion, said central portion being so formed that the cross-sectional area of said flow path is least at a position adjacent to but upstream from said cavity, a single rotating blade member having a profile of aerodynamic design mounted for rotation in said cavity, the axis of rotation of said member being positioned transversely to the direction of flow of said fluid medium across said cavity and parallel to the mean plane of the flow surface of said central portion adjoining said cavity, and means associated with said member having an output proportional to the speed of rotation of said member, said member being so dimensioned and positioned that at one position at least an edge portion of said member in rotating penetrates the main flow stream of said fluid medium over said cavity and at another position said rotating member is contained substantially entirely within said cavity, whereby to cause said member when said fluid medium flows through said flow path to experience successively primarily aerodynamic lift, dynamic, and static pressure forces each tending to rotate the member and sufficient in the aggregate to sustain continuous rotation of said member.

3. A flowmeter according to claim 2 wherein said associated means comprise an electrically energized sensing unit, which is part of a tuned oscillating circuit, including at least one reactance circuit element disposed so that its reactive impedance varies in sympathy with the rotation of said member; said output being an amplitude or frequency modulation of the high frequency carrier of the tuned oscillator being presented across a set of terminals connected to said circuit element.

4. A flowmeter according to claim 2 wherein said associated means comprises an electrically energized sensing unit including an inductance coil, adapted to be supplied with electrical high frequency energy from a suitable oscillator, positioned adjacent said rotating member, whereby said member's edges in rotating cut the electromagnetic lines of force surrounding said coil due to the electrical energy flowing therethrough.

5. A flowmeter according to claim 2 wherein said means associated with said rotating member comprises an electrically energized sensing unit, including a condenser adapted to be part of a tuned oscillating circuit and supplied with high frequency energy from this oscillator, one plate of said condenser being in electrical contact with said rotating member and the other plate being isolated from said rotating member but positioned adjacent

to it whereby rotation of said rotating member is effective to vary the capacitance of said condenser and hence the capacitive reactance present at the terminals of said condenser and causing an amplitude or frequency modulation of the oscillator high frequency carrier.

6. A flowmeter according to claim 1 wherein said single rotating blade member is so dimensioned and positioned as to cause said member in rotating to project into the main flow stream of said fluid medium passing said cavity a distance equal to from about 20% to about 30% of the diameter of the cylinder swept by said member in rotating.

7. A flowmeter for determining the rate of flow of a fluid medium in a conduit comprising a casing having a generally cylindrical bore therethrough; means at either end of said casing for connecting said casing to said conduit; an inlet portion integrated with said casing, effective to contract the cross-sectional area of the flow path of said fluid medium in said bore in a downstream direction, said inlet portion having a substantially flat flow surface whereby said inlet portion's flat flow surface essentially forms chords of the circle defined by said bore and said contraction increases smoothly and continuously throughout the length of said inlet portion; a flared outlet portion colinear with and downstream of said inlet portion and integrated with said casing, downstream of said inlet portion, said outlet portion being effective to expand the cross-sectional area of said flow path in a downstream direction and having a substantially flat flow surface whereby said outlet portion's flat flow surface essentially forms chords of the circle defined by said bore and said expansion increases smoothly and continuously throughout the length of said outlet portion, the cross-sectional area of said flow path at the upstream end of said outlet portion being not less than that at the downstream end of said inlet portion; a central portion located between said inlet and outlet portions and colinear therewith, the flow surfaces of said central portion at the upstream and downstream edges thereof being contiguous with the downstream and upstream edges of said associated inlet and outlet portions respectively; means defining a cylindrical cavity in the flow surface of said central portion, the longitudinal axis of said cavity being transverse to the direction of flow of said fluid medium and substantially parallel to the downstream edge of said flat flow surface of said inlet portion, and the walls of said cavity being interrupted over a portion of their circumference whereby to provide communication between said cavity and said bore immediately adjacent said cavity; an elongated single rotating blade member having a profile of aerodynamic design mounted for rotation in said cavity about a longitudinal axis, said axis being coincident with that of said cavity and said member in its rotation having one position whereat one edge of said member projects through the interruption in the walls of said cavity and another position whereat said rotating member is contained substantially entirely within said cavity; and means associated with said rotating member having an output proportional to the speed of rotation of said member.

8. A flowmeter according to claim 7 wherein said flat flow surface of said flared outlet portion subtends an angle of from 5 to 15 degrees with the axis of said bore, and the said flat flow surface of said flared inlet portion subtends an angle lying in the range of from 10 to 20 degrees with said axis of said bore.

9. A flowmeter according to claim 1, wherein a cylindrical liner is fitted snugly within said cavity, said liner being axially displaceable from said cavity and being provided with a slot providing communication between its interior and said flow path, said rotating member being rotatably mounted inside said liner and removable therewith, said liner being rotatable so that its interior may be isolated from said flow path, said liner being further provided with means for attaching thereto a cylindrical rod of diameter identical with that of said

liner whereby said liner may be axially displaced and replaced by said rod.

10. A flowmeter according to claim 1 wherein said single rotating blade member is so dimensioned and positioned as to cause said member in rotating to project into the main flow stream of said fluid medium passing said cavity a distance equal to substantially about 50% of the diameter of the cylinder swept by said member in rotating.
